DATING OR NUMBERING MECHANISM

Michael J. Milmoe, Glen Ellyn, and Clarence J. Malhot, Oak Park, Ill., assignors to F. B. Redington Co., Chicago, Ill., a corporation of Illinois

Application April 5, 1937, Serial No. 135,084

5 Claims. (Cl. 101—24)

This invention relates to dating or numbering mechanism and particularly to that type of apparatus which punches holes in a web or sheet to represent the date of packaging an article or 5 the series number of the packaged article.

An important object of the invention is the provision of a new and novel dating or numbering mechanism employing perforating apparatus having a rotatably mounted perforating head 10 carrying the perforating dies which engage grooves formed in a roller co-operating with the dies, the dies being arranged and configurated so as to perforate the sheet, but not entirely, whereby the punches are still integrally attached to 15 the web to be pressed against a surface of the web by means designed and arranged for that purpose.

A further object of the invention is to provide a dating or numbering mechanism which partially 20 punches through the paper leaving the punch-outs integrally attached to the sheet or web, thereby preventing any punch-out or material of the web from becoming commingled with the material which comes in contact therewith, there 25 being means provided to flatten out and bend the partial punch-outs against the web to prevent their being torn but at the same time leaving a clear perforation.

Numerous other objects and advantages will be 30 apparent throughout the progress of the following specification.

The accompanying drawings illustrate a selected embodiment of the invention and the views therein are as follows:

35 Fig. 1 is a detail diagrammatic or schematic view showing the web feeding, perforating, and cutting elements and the means for operating them;

40 Fig. 2 is a detail elevational view of the web feeding, perforating, and cutting elements and the operating mechanism therefor;

Fig. 3 is a detail sectional view showing the 45 perforating die and its co-operating roll;

Fig. 4 is a detail sectional view on the line 4—45 of Fig. 3;

Fig. 5 is a detail plan view of the perforating 50 element looking in the direction of the arrows 5—5 of Fig. 4;

Fig. 6 is a detail plan view of the web after it 55 has been punched or perforated; and

Fig. 7 is a detail sectional view of the web on the line 7—7 of Fig. 6.

The particular dating or numbering mechanism herein shown for the purpose of illustrating the 55 invention comprises a frame 10 upon which there

is mounted a shaft 11 carrying a roll 12 of webbing 13 such as parchment, paper, or other similar material. In the particular embodiment herein shown the webbing 13 is a fibrous material or parchment which is used for wrapping butter, oleomargarine, or other similar commodity. The web or webbing 13 passes over a driven roller 14 mounted on a shaft 15. The driven roller 14 has meshing relation with a driving gear 16 mounted on the perforator shaft 17. 10 A perforator segment 18 is fixed to the perforator shaft 17 and carries dies 19 having a plurality of perforating pins 20. The perforating pins 20 co-operate with circumferential grooves 21 formed in the co-operating driven roll or platen 15 roll 14. The segment 18 is fixed to the shaft 17 and rotates therewith, and inasmuch as the shaft 17 is driven from the drive shaft 15, the roll 14 and the shaft 17 rotate at predetermined speeds whereby the die 19 is brought into perforating 20 engagement with the web 13 every revolution of the shaft 17. Therefore, the perforation of the web can be accomplished at desired spacings on the web.

The perforating pins 20 are provided with 23 beveled edges 22, Fig. 3, so that punchings or flaps 23 will be punched from the web 13. The flaps or punches 23 will have an intact portion 24 integrally connecting them to the body of the web, thereby providing downwardly extending 30 portions connected to the web, Fig. 7, and the perforated openings 25.

The web 13, after it is punched by the pins 20, passes over a driven roller 26, Fig. 1, mounted on the shaft 27. The shaft 27 is driven by an idler 35 gear 28 mounted on a shaft 29. The idler gear 28 has meshing relationship with a gear on the shaft 15 and is driven thereby. It also has meshing relationship with the gear on the shaft 27 and drives the shaft 27.

Measuring feed rolls 30 and 31 mounted on shafts 32 and 33, respectively, are driven by an idler gear 34 having meshing relationship with gears on the shafts 27 and 33. The web 13 passes between the measuring feed rolls and feeds the 45 web to the cutters 35 and 36 mounted on the cutter shafts 37 and 38, respectively. The cutter shafts 37 and 38 are driven by an idler gear 39 having meshing relationship with gears on the shafts 33 and 38. The shafts 32 and 33, and the 50 shafts 37 and 38, have meshing relationship so they are driven synchronously in opposite directions and in timed relationship with each other. The cutter rolls 35 and 36 are provided with cutters or knives 40 and 41, respectively, Fig. 1. 55

A blade element 42 is arranged preferably between the driven roller 14 and the roller 26 and extends upwardly from its base 43, being relatively perpendicular to the web 13 as the web passes from the roll 14 to the roll 26. This blade element 42 has its upper surface beveled as indicated at 44, Fig. 7, with its longer edge 45 arranged toward the oncoming web, and its purpose is to engage the downwardly hanging partially punched out pieces 23 and bend them back against the face of the webbing as indicated at 46, Fig. 7, whereby the integral contacting punch elements 23 are left fixed to the web but bent back, preventing any particles from sticking to the material which is to be wrapped in the webbing but permitting clean perforations which can be easily and readily seen and deciphered.

The invention therefore provides a simple device for feeding a parchment to perforating position where it is perforated, and then feeding it to cutting position where the cutters 40 and 41 cut the web into wrapper lengths. The entire elements from the roller 14 to the cutters 40 and 41 are operated in proper timed relationship to properly feed the web and to cut it at predetermined lengths.

During the present description it was stated that the shaft 15 could be the drive shaft, but in practice it has been found convenient, due to the location of the cutters, to drive the shaft 38, the other gears and shafts being driven from this latter shaft. However, inasmuch as all the devices are geared together, any one of the gears may be the driving gear.

The web after it is cut is provided with clear perforations, which perforations are formed by the perforating pins 20 which do not entirely cut out the paper, but leave punch-outs 23 fastened integrally to the main web 13 by the intact portions 24. The intact portions 24 are bent over by the blade 42 and are forced back against a surface of the web. These portions when they are bent back as indicated at 46 are further pressed against the web as the web passes over the roll 26 and between the measuring rolls 30 and 31. The pins 20 are part of the dies 19, the dies being fixed in the segments 18, Fig. 4, by the fastening or locking members 47.

It will be seen from Fig. 5 that the perforating pins 20 of the dies 19 are arranged in columns and rows to form numerals indicative of the date or number of the packaged articles. It will be evident that from day to day or from series to series, other dies, having perforated pins 20 arranged in columns and rows, may be substituted for the particular die shown, the pins 20 mating with the circumferential grooves 21 in the plate and roller 14.

The particular device herein disclosed for the purpose of illustrating the invention comprises few and simple, positively operating parts which are correlated and operate in proper timed relationship synchronously, and the arrangement of providing connected punchings or flaps prevents particles of the webbing or material from becoming commingled with or sticking to the material to be wrapped, a condition which would exist were the punchings completely severed from the material.

Changes may be made in the form, construction and arrangement of the parts without departing from the spirit of the invention or sacrificing any of its advantages, and the right is hereby reserved to make all such changes as

fairly fall within the scope of the following claims.

The invention is hereby claimed as follows:

1. Mechanism for impressing a date or number in a sheet of wrapping material, comprising a rotary member out of contact with the sheet and on one side thereof, said member carrying radially projecting bevelled punching pins spaced in outline of desired characters, a roller on the opposite side of the sheet and having peripheral grooves therein to receive the pins carried by the rotary member, means for positively driving said roller and said pin-carrying member to punch the characters therein as the sheet is fed, said pins cooperating with the grooves in the roller to punch out portions of the sheet and to leave the punched-out portions integrally connected with the sheet, and means on the same side of the sheet as the grooved roller for engaging the punched-out portions and folding them back against the surface of the sheet. 5

the surface of the material on the same side as the grooved roll for engaging the flaps to fold the flaps back toward the surface of the material.

5. A dating or numbering device for wrapping material, comprising a rotary roll on one side of the material and engaging the same on one side thereof and having peripheral grooves therein, a rotary element adjacent said roll on the opposite side of the material, pins on said element arranged in outline of the desired characters and adapted to register with said grooves, said pins each having a bevelled cutting surface, driving and driven gears interconnecting said roll and

said rotary element for synchronous rotation, the pins carried by the rotary element cooperating with the grooves in the rotary roll to punch from the material projecting flaps each integrally connected to the material, a bevelled blade adjacent the surface of the material on the same side as the grooved roll for engaging the flaps to fold the flaps back toward the surface of the material, and roller means subsequently engaging the material for further pressing the flaps against the surface of the material. 5
